ASH TRAY

Jasper A. Moore, Houston, Tex.

Application October 5, 1950, Serial No. 12,467

Term of patent 7 years

(Cl. D85—2)

To all whom it may concern:

Be it known that I, Jasper A. Moore, a citizen of the United States of America, residing at Houston, in the county of Harris and State of Texas, have invented a new, original, and ornamental Design for an Ash Tray, of which the following is a specification, reference being had to the accompanying drawing, forming part thereof.

Fig. 1 is a perspective view of an ash tray, showing my new design.

Fig. 2 is a top plan view thereof; and

Fig. 3 is a side elevational view thereof.

The side of the tray not shown has substantially the same appearance as the side shown in Fig. 3.

I claim:

The ornamental design for an ash tray, as shown and described.

JASPER A. MOORE.
